UNITED STATES PATENT OFFICE

EARLE M. CROSBY, OF BIRMINGHAM, MICHIGAN, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

FASTENER SETTING MACHINE

Application filed November 8, 1927. Serial No. 231,959.

This invention relates to machines for handling fasteners, more particularly to machines for setting snap fasteners or parts of such fasteners in sheet material. The invention is herein disclosed as embodied in a machine for setting the socket members and back plates or washer plate members of snap fasteners and for convenience these terms will be used as referring generally to any fasteners comprising complementary parts.

While certain features of the present invention are applicable to the setting of fasteners broadly, other features of importance relate to mechanism for handling fasteners of the particular type which have unequally spaced pairs of attaching prongs, and, in one of its aspects, the present invention consists broadly in the provision of assorting mechanism for handling fasteners of this type.

Another problem with which this invention deals consists in the proper assorting and presenting for delivery of a back plate or washer plate having unequally spaced pairs of apertures to receive the prongs of the fastener part above referred to.

In machines designed to set fasteners spaced inwardly from the edge of work as for example in automobile curtains, rugs or the like, the increased width of throat required to permit the introduction of the work necessitates transferring the fastener parts through relatively long distances from the hoppers to the setting mechanism. In another of its aspects the present invention consists in the provision of improved mechanism for effecting such transfer rapidly and reliably and in accurately bringing together the fastener parts in setting position.

These and other features of the invention will be best understood and appreciated from the following description of a preferred embodiment thereof selected for purposes of illustration and shown in the accompanying drawings, in which

Fig. 1 is a view of the complete machine in side elevation.

Fig. 2 is a view on a larger scale of the machine in side elevation with the parts thereof shown in longitudinal section.

Fig. 3 is a transverse sectional view show-

ing details of the fastener transferring operating mechanism.

Figs. 4 and 5 are fragmentary views in side elevation and front elevation respectively of the fastener separating mechanism.

Fig. 6 is a view in transverse section of the fastener transferring mechanism.

Fig. 7 is a view in horizontal section of washer plate transferring mechanism shown in its relation to the upsetting die.

Figs. 8 and 9 are views in plan and side elevation of the washer plate raceway and associated mechanism.

Fig. 10 is a detailed view of a portion of the washer plate transferring mechanism shown in Fig. 7.

Figs. 11 and 12 show the pronged fastener part in inverted plan and side elevation respectively.

Figs. 13 and 14 are similar views of the washer plate.

Fig. 15 is a plan view of the two hoppers and their driving mechanism.

Fig. 16 is a sectional view of the hopper for the principal or pronged fastener part.

Fig. 17 is a fragmentary inverted plan view of the ring of this hopper.

Fig. 18 is a fragmentary sectional view of the same.

Fig. 19 is a view in section of the hopper for the washer plates.

Fig. 20 is a fragmentary sectional view on an enlarged scale.

Fig. 21 is a fragmentary view on a section at right angles to that of Fig. 20.

Fig. 22 is a fragmentary view in inverted plan of the ring in the washer plate hopper.

Fig. 23 is a fragmentary sectional view similar to Fig. 20 but showing a washer plate in different positions.

Fig. 24 is a view of the machine in front elevation, certain parts being shown in section.

Figs. 25 to 31 inclusive are fragmentary views on an enlarged scale of the upsetting die and the delivery end of the washer plate raceway.

The machine shown comprises a hopper for sorting the pronged members of the fastener, another hopper for sorting the back plates,

raceways for conveying these fastener parts to the setting mechanism, means for transferring the fastener parts in a definite manner to the setting point, and mechanism for setting or clinching the two fastener parts upon the work. The detailed description of the various mechanisms will be taken up in substantially the order in which they have been enumerated.

As shown in Figs. 11 to 14, the type of fastener which this machine is particularly designed to handle consists of a spring socket member adapted to receive a suitable stud. This member comprises an oval sheet metal body 2 provided with a series of four projecting prongs, indicated by reference character 3 and located in pairs near each end of the body of the fastener, the pair at one end being located closer together than the pair at the other end as will be seen in Fig. 11. These prongs project through a plate 5 to which the body 2 is fastened by four small tongues clinched over on the surface of the plate. Between these two parts of the fastener are retained spring wire members 6 which will yieldingly engage the stud when the fastener is in service.

In setting these fasteners the prongs 3 are forced through the material, passed through a perforated washer plate and then clinched on the surface of the washer plate. The washer plate is shown in Figs. 13 and 14. It has a pair of apertures 7 located at each end to correspond in position with the prongs of the body part 2, that is to say, the pair at one end being closer together than the pair at the other end. It also has a circular perforation 8 located nearer to one end than the other, for a purpose which will be presently described, and a series of bosses 9 on one surface and corresponding recesses on the other for the reception of the small tongues clinched on the bottom plate of the other fastener part.

The mechanism for sorting and arranging these fastener parts properly for the setting operation comprises a pair of hoppers located on a bracket 82 at the rear part of the machine, inclined downwardly and forwardly, and each discharging into a raceway.

The hopper for the pronged fastener parts or socket members shown in Figs. 11 and 12, has a stationary circular base portion 10 in which is mounted an inclined shaft 12 carrying a rotary bowl 13. Secured to the lower edge of the bowl is a ring 14 with a bevelled inner edge, as shown in Figs. 16 and 18, which forms to all intents and purposes a part of the bowl and rests on the upper surface of the hopper bottom 10. The bowl 13 has a series of vanes 11 forming pockets for the fastener parts and is connected to its central sleeve by radial webs, as shown in Fig. 16. It will be understood that as the bowl is rotated the fasteners are carried in the pockets formed by the vanes to the high side of the bowl and

then fall by gravity against the lower wall of the hopper and tumble about freely, assuming different positions which eventually permit them to leave the hopper by the discharge ports. 70

In order to permit the escape of the fasteners from the hopper the ring 14 is provided with a series of projections 15 between which are passages or guideways of suitable dimensions to permit the fasteners to pass through them. It is necessary however to deliver the fasteners with their prongs pointing upwardly and for the purpose of permitting the passage of those fasteners only which are arranged in this manner and rejecting those which are wrong side up each passage is provided with a stop in the form of a pin 16 which projects into the top of the passage. The end of each pin 16, however, is spaced far enough from the bottom of the guideway to permit the body of a fastener to pass under it if the prongs are uppermost. If the prongs are not uppermost the pin 16 prevents the passage of the fastener by engaging its body part. This will be apparent from an inspection of Fig. 18 where the fastener is indicated in dotted lines. 80 85

In addition to delivering the fastener right side up it is also necessary to deliver it right end foremost, that is to say with the end foremost having the widely spaced prongs 3. To bring this about the diameter of the pin 16 is made less than the distance between the widely spaced prongs 3 but greater than the distance between the closely spaced prongs 3 so that unless the fastener comes right side up and also right end foremost it cannot pass the stop pin 16. In Fig. 18 the fastener is shown in the proper position to be discharged, the widely spaced prongs having passed by the stop pin. By the time the rear prongs engage the pin 16 the body of the fastener has advanced far enough to drop into the groove in the base 10 and thus allow the rear prongs to slip under the end of the pin 16. 100 105 110

The hopper bottom 10 is provided with a depressed annular groove to receive a series of projections 17 extending a step beyond or below the projections 15 of the ring 14, these projections having side walls forming a continuation of the discharge passage at a lower step or level. The walls of the ring projections 15 and 17 do not extend radially with respect to the hopper but are disposed tangent to a circle concentric to the axis of the hopper. This feature of construction has been found important in the satisfactory handling of the fasteners here in question. 115 120

As the hopper rotates slowly in a counter clock-wise direction, Fig. 15, fasteners which are positioned right side up and right end foremost slide through the passages and pass the pins 16, advancing into the lower level of the stepped passage in the ring of the hopper bottom 10. These properly positioned 125 130

fasteners are thereupon carried around in the recesses between the walls of the projections 17 until they arrive at a point on the inner or right hand side of the hopper as seen in Fig. 15, where they can slide outwardly into the receiving end 18 of the raceway which, it will be seen, encircles the hopper for nearly one half of its circumference.

The receiving end 18 of the raceway is shaped to conduct the pronged fastener parts to the upper end of the raceway proper. This consists of a flat plate 20 upon which the fasteners slide back downward, and a centrally disposed rail 21 spaced above the plate 20 and arranged to be straddled by the prongs of the fastener. The gravity raceway 20-21 leads from the hopper to the screw conveyor 27 by which the final step in the feeding of the fastener to the setting die is effected.

The mechanism for sorting and arranging the washer plates shown in Figs. 13 and 14 consists of a hopper with a stationary circular base 70 and bowl 73 journaled on a shaft 72. A ring 74 having a bevelled inner edge forms the lower part of the bowl 73 and rests upon the base part 70. The base 70 has a stepped groove therein and the bottom of the ring has stepped projections which fit the grooves. Shallow passages 75 are provided in the bottom face of the ring 74 between these projections. The passages are not quite radial in their direction but tangent to a small circle concentric to the axis of the hopper. As in the case of the pronged fastener parts, it is necessary that the washer plates should be arranged right side up and right end foremost in leaving the hopper. To this end the passages 75 are shaped so as to permit the passage of the washer plate only when the plate is positioned with the bosses 9 uppermost. As will be seen from an inspection of Figs. 20 and 22 the passage 75 has a shoulder at each edge which narrows it so that the body of the washer plate cannot enter it if elevated by having the bosses 9 beneath it. If on the other hand the bosses project upwardly they will pass freely through the central part of the passage.

In order to insure passage only of those washer plates which enter right end foremost a stop pin 76 projects downwardly from the ring 74 into each passage 75. As already pointed out the central aperture in the washer plate is located nearer to one end than the other and the arrangement of the stop pin 76 in the passage is such that only those washer plates may pass it which approach short end foremost, that is to say, with the end foremost to which the perforation is nearest. As the washer plate passes into the passage 75 it tips downwardly and enters the recess 77 formed in the hopper bottom 70 between the projections of the ring 74, assuming the angular position shown in Fig. 20 or in Fig. 23. If the washer plate

does not arrive right end foremost the stop pin 76 prevents it from entering the recess 77 by engaging its surface as shown in Fig. 23. If however, the washer plate is right end foremost the perforation 8 in it affords 70 clearance for the end of the stop pin 76 so that the plate may advance sufficiently to drop completely into the recess 77 as clearly indicated in Fig. 20. When this occurs the 75 properly located washer plate is carried in its recess in the clockwise movement of the hopper into the inner or left hand edge thereof, as seen in Fig. 15, until it reaches a point where it may pass outwardly from the recess into the receiving end 78 of the raceway.

It will be noted that the lower end of the stop pin 76 is centrally recessed to permit passage of the centrally disposed bosses 9 of the washer plate. The receiving end 78 of 85 the raceway conducts the plates to the upper end of the raceway proper 102 which has undercut side flanges properly proportioned to permit the free passage of washer plates. 90 This leads from the hopper to the upsetting die to which the plates finally are delivered as will presently appear.

The bowls of both hoppers are driven by a single belt 80 from a pulley 81 on the rear end of the main shaft 33, located just inside the hand wheel 50. The two hoppers are carried by a bracket 82 bolted to the rear part of the main frame and having journaled in its rear upper side a shaft 83. This shaft carries a driven pulley 84 fast on its lower end and a driving pulley 85 fast on its upper end. It also carries a loose sleeve 86 having a driven pulley 87 at its lower end and a driving pulley 88 at its upper end. Arms extending downwardly from the bracket 82 carry an idler shaft 91 upon which are mounted three idlers 92, 93 and 94, as shown in Fig. 15. The circumference of each ring 14 and 74 of the hoppers is grooved to receive the driving belt 80. This belt, as shown in Figs. 1 and 15, passes upwardly from the right hand side of its driving pulley 81 over the idler 92, and about the driven pulley 87, imparting a clock-wise rotation to the driving pulley 88 on the sleeve 86 which, in turn, is 110 transmitted through the belt 95 to the right hand hopper as a clock-wise rotation.

The belt 80 after leaving the pulley 87 passes over the idler 93, then as a cross belt to the driven pulley 84 imparting to that, and 120 to the driving pulley 85, a counter clock-wise rotation. It then passes from the pulley 84 over the idler 94 and back to the driving pulley 81. The counter clock-wise rotation of the pulley 85 is transmitted to the left hand hopper through a belt 96 as a counter clock-wise rotation. The grooved ring 74 of the washer plate hopper is located substantially in the plane of the driving pulley 85, while the grooved ring 14 of the pronged 130

fasteners is located somewhat lower and substantially in the plane of the driving pulley 88.

A pair of belt tightening pulleys 99 and 100 are carried by a head 98 which may be adjusted upon the bracket 82 to maintain a proper tension on the driving belts.

Referring again to the raceway for the pronged fasteners, it will be seen that the 10 rail 21 is held in place by a pair of arms 15 22 projecting from the plate 20 near its upper end and by a transverse pin 23 passing through the lower end. This raceway conducts the fasteners to a screw conveyer of 20 the general type disclosed and claimed in my co-pending application Serial No. 153,549, filed December 9, 1926. This conveyor comprises a barrel 27 having square threads upon its body part, so spaced as to accommodate 25 the fasteners between them. The screw is supported horizontally by a driven shaft 28 at its rear end and is journalled in the machine frame at its forward end. It is driven intermittently by a Geneva movement, a Geneva wheel 31 being fast on the shaft 28 and the driven member 32 fast on the main shaft 33. The latter shaft is provided with a pulley 24 so that it may be belted to any convenient 30 source of power. This mechanism gives the screw 27 a quarter revolution for each complete revolution of the main shaft, and in each such movement one fastener is delivered to the setting die 29 on the setting plunger 40.

A mechanism for separating the fasteners 35 in the raceway 20—21 and discharging them one by one to the screw conveyor is provided. It comprises a forked escapement member 55 secured to a saddle piece 54 which is pivotally mounted by a pin 57 on ears 56 projecting upwardly from the raceway plate 20, (see particularly Figs. 2, 4 and 5). The escapement piece is forked at both ends to straddle the raceway rail 21 and one end or the other stands in the path of the fastener 40 prongs. The saddle member 54 is provided with an upstanding ear 58 which is connected through a tension spring 59 to the raceway rail 21, in such manner as to tend to swing the escapement always in a counter clock-wise 45 direction. This saddle piece has also an outwardly extending arm 60 which is engaged by an adjustable stop screw 61 in a block 62 carried by an actuating rod 46. As shown in Fig. 4 the actuating rod 46 is in its elevated position. When it is lowered the spring 59 rocks the escapement member 55, carrying its upper end out of the path of the prongs of the endmost fastener on the raceway and allowing the fastener to pass downwardly until its encounters the lower end of the escapement member which has now been rocked into operative position. When the actuating rod 46 is again lifted, the fastener engaged by the lower end of the escapement 60 member is permitted to pass freely down

the raceway while its upper end engages the succeeding fastener and again occupies the position shown in Fig. 4.

Means are provided for positively insuring the delivery of the fastener released by the 70 escapement mechanism to the screw conveyor 27. This comprises a pusher arm 64 pivotally mounted upon the block 62 and maintained at all times by a spring 66, against the pin, 65 in the raceway rail 21. The pusher arm 75 64 has an inclined rear edge which acts as a cam when the actuating rod 46 is lowered to cause the pusher arm to travel forwardly at its lower end, engaging the endmost fastener, and forcing it positively from the 80 raceway to the screw conveyor. The pusher arm is forked as shown in Fig. 5 and adapted to advance the fastener by engaging its upstanding prongs.

The pronged fasteners are delivered to the 85 screw conveyor 27, with the prongs uppermost, as they leave the raceway, and straddling a straight bar 26 disposed parallel to the axis of the screw conveyor. This forms the central member of a guideway or raceway section leading to the setting die 29. The action of the screw thread cams the fasteners along this guideway and into position in the setting die.

The actuating rod 46, as shown in Fig. 3, 90 is connected at its lower end to a plunger 40, slotted to receive the end of a cam lever 36 which is pivotally mounted in a socket head 37 bolted to the machine frame 30. The cam lever 36 carries a cam roll 38 which is 10 depressed by a cam 35 on the main shaft 33. This cam lever is elevated and held in contact with the cam by a tension spring 39. The motion of the cam is cushioned in being transmitted to the plunger 40 by a compression spring 42 which acts on the under side of the operating end of the cam lever 36 and is located in a socket in the plunger, the spring being backed up by a nut 43. The chief function of this spring is to prevent breaking 11 the parts in the event of a jam.

At its upper end the actuating rod 46 is guided in its movement by, and actuates, a rocker member 48, Figs. 2 and 24, fast to a transverse shaft 49 which is journalled in the 11 upper branch 44 of the main frame. The rocker member 48 and shaft 49 operate mechanism for transferring the washer plates in the raceway 102 and delivering them to the upsetting die and this mechanism will now 12 be explained.

The washer plates are arrested in their movement down the raceway by a pair of spring detents 104, Figs. 8 and 9, set in opposite sides of the raceway and acting to engage the foremost plate. The plates are fed past the detents 104 by a feeding member 106 mounted in a plate 108 fastened to one side of the raceway and having a straight longitudinal slot 109 and a cam shaped longitudi- 13

nal slot 110. A pin 111 connects the feed member 106 to the plate 108 at the slot 109, permitting the feed member 106 to move parallel to the raceway and also to rock toward and from it. Spring washers on this pin exert a slight frictional resistance to the movement of the part 106. A cam pin 112 projects from the feed member 106 into the cam slot 110 and controls the rocking movement of the feed member as it is moved longitudinally. The feed member 106 is operated through a spring 122 and a rod 114 which passes through a block 116 pivotally mounted on the upper end of a rocker arm 118 secured to the outer end of the rock shaft 49, above mentioned. The rod 114 also carries an adjustable collar 120 between which and the compression spring 122 the block 116 is located.

It will be apparent that when the rocker arm 118 is swung in a clock-wise direction the feed member 106 will be moved bodily toward the right, as shown in Fig. 9, and that this member will also be rocked away from the raceway so that its end travels in a path above the washer plates in the raceway as determined by the upper edge of a cam slot 110. On the other hand when the rocker arm 118 is moved in the opposite direction, the feed member 106 is moved toward the left, as seen in Fig. 9, and at the same time its operative end is swung down toward the raceway into a position wherein it engages the central aperture of the endmost washer plate. The movement of the feed member is then momentarily interrupted and the spring 122 compressed until a propelling force is built up sufficient to overcome the resistance of the detents 104 and to shoot the fastener past said detents. When this occurs the lower edge of the cam slot 110 again elevates the feeding member so that as the washer plate is freed from the detents it is also freed from the feeding member, and by the combined action of the detents and the spring 122 is shot along the raceway to the delivery end thereof where it is arrested by a second pair of detents 130, (see also Fig. 31).

The construction of the upsetting die will now be described after which further attention will be given to the mechanism for transferring and delivering the washer plate from the raceway 120 to the die.

The upsetting die 150 is mounted in a stationary position but with adjustable yielding backing in the upper branch 44 of the machine frame. Its normal position is determined by a flange 152 which engages a shoulder formed in the bore of the mounting. It is keyed in position to prevent rotation and backed up by a heavy compression spring 154 having at its upper end the recessed cap 156 for a hardened ball 158. This, in turn, is engaged by an adjusting screw 160 threaded into a cap 162 which closes the

bore in the frame. The amount of initial tension in the spring 154 may be adjusted by turning the screw 160. The upsetting die 150 is drilled to receive a pilot plunger 164 whose function is positively to locate the washer plates in position prior to the setting operation and then to retract to disengage the completed fastener and permit the work to be removed conveniently from the machine. The pilot plunger 164 is apertured near its upper end to receive one arm of a bell crank lever 166 by which it is operated as will be presently described.

At its lower end the upsetting die has a pair of flanged retaining or holding members for the washer plate. These are shown in Figs. 25 to 30 and comprise angular flanged plates 170 and 172 forming, in effect, a continuation of the raceway 120 and each having ears to receive pivot pins 174 extending into the body of the upsetting die 150 in a direction parallel to the length of the raceway 120. The flange plates 170 and 172 are free to swing outwardly but are maintained yieldingly in the position shown in Fig. 29 by springs 176, one passing through the head of each pivot pin 174, and being hooked into apertures formed for that purpose in the angular plates 170 and 172. It will be understood that these springs not only maintain the angular plates 170 and 172 in position but also serve to retain the pivot pins 174 against displacement.

The bell crank lever 166 which operates the pilot plunger 164 is pivotally mounted in the frame of the machine and carries a pivoted arm 167, having a pin and slot connection therewith permitting yielding movement in one direction against a spring 168 which extends between the arm 167 and an ear on the bell crank lever 166. The arm 167 is connected to a telescopic link 169 pivotally connected with the rocker member 48 above referred to.

A feeding member 180, Figs. 2, 25 and 26, is provided for advancing the washer plates past the detents 130 in a manner somewhat similar to that in which the feeding member 106 advances them past the detents 104. The feeding member 180 is pivotally mounted upon the forward end of the rocker member 48 and is actuated thereby. Near its lower end it has a transverse pin 183 which cooperates with an oblique cam surface 182 to impart a four-motion feeding movement to the end of the member 180 as it is moved back and forth by the oscillation of the rocker member 48. When the member 180 is moved toward the right as shown in Fig. 26 this cam surface 182 lifts the end of the feeder so that it is drawn back out of contact with the washer plate held at the end of the raceway. This movement of the feeding member 180 is sufficient to carry the pin completely above the cam surface so that the end of the

feeding member is permitted to drop toward the raceway and engage the washer plate prior to its advancing feeding movement. During this feeding movement the pin 5 183 passes beneath the cam surface 182 instead of above it, as shown in Fig. 26. The feeding movement disengages the washer plate from the detents 180 and carries it positively to the carrier formed by the 10 flanged angular plates 170 and 172 beneath the upsetting die.

The oblique cam surface 182 is formed on a part of the bail shaped member 184 of sheet metal which is permanently mounted for 15 swinging movement on pins 185 in the raceway 102. It will be apparent that this construction permits the pin 183 on the feeding member 180, during its feeding stroke, to pass under the oblique surface and momentarily lift this with the member 184. The bail shaped member 184 is provided with a pair of forwardly extending arms having in-turned ends which are received in slots formed respectively in the rear ends of the 25 angular flanged plates 170 and 172.

A second feeding member 50 is provided for positively advancing the washer plate as delivered to the carrier 170 and 172 into substantial alignment with the pilot plunger 164. 30 This feeding member 50 comprises a bent rod pivotally connected at its rear end, with provision for adjustment, to an arm 51 formed integral with the rocker member 48. At its forward end the feed member 50 is guided by 35 passing through a perforated ear 52 formed on a plate secured to the lower side of the raceway 102. It pushes the washer plate forward on the carrier arms 170 and 172 and completes its delivery to the setting mechanism. 40

The construction and operation of the setting die is similar to that of the corresponding member disclosed in my co-pending application above identified. It comprises a 45 plunger 34 guided for vertical movement and carrying a cam roll 42, as shown in Figs. 2 and 24. The cam roll 42 runs upon a single throw cam 41 carried at the forward end of the main shaft 33. A spring 40 depresses the plunger 34 and maintains the cam roll in engagement with the periphery of the cam 41. The plunger 34 is provided with a socket at its upper end to receive a replaceable hardened setting die 29 which is concave to receive 50 and support a pronged fastener during the setting operation.

From the foregoing description the operation of the machine herein shown will be clearly understood.

60 The machine comes to rest with a fastener delivered to the setting die and a washer plate delivered to the upsetting die. When the machine is tripped the setting die is at once elevated, the prongs of the fastener passing through the work and through the wash-

er plate held by the flanged plates 170 and 172 in position on the upsetting die and being clinched against the upsetting die. It will be noted that the angular plates 170 and 172 are provided with tapering projections (see Figs. 29 and 30). These are engaged by the lower die in its upward movement and results in separating the angular plates so as to permit the washer plate to rest upon the upper surface of the work. Near the conclusion of the setting operation the pilot plunger 164 is retracted and the operator is free to remove the work with the clinched fastener from the machine.

It will be observed that the problem of advancing the fastener parts through the relatively long distances at the upper and lower sides of the throat has been solved very effectively, the screw conveyor producing this transfer at the lower side of the throat, while the upper raceway with the mechanism for shooting the washer plates through it to parts which then deliver them to the setting die, performs this function very satisfactorily at the upper side of the throat.

In my copending application Ser. No. 153,549, filed December 9, 1926, I have disclosed means for assorting pronged fasteners of a different type from those for which the present machine is particularly adapted. In one of its aspects the present invention is a carrying forward or further development of the broad invention of my earlier application and is within the scope of certain claims therein presented.

While I have herein shown and described the mechanism which best embodies my invention up to the present time it will be understood that the invention may be embodied in other mechanisms without departing from the spirit or scope thereof.

Having thus described my invention, what I desire to claim as new is,

1. Assorting mechanism for fasteners having widely and closely spaced pairs of projections, comprising a hopper having a discharge passage, and a stop normally projecting into said discharge passage for preventing progress of a fastener in the passage except when the widely spaced projections occupy a position in advance of the closely spaced projections during passage of a fastener part through the discharge passage.

2. Assorting mechanism for fasteners having prongs, comprising a hopper having a discharge passage provided with a stepped bottom, and means located in said passage for preventing a fastener from advancing from one step to the next step of the bottom of the passage when the fastener is entered with the prongs in a predetermined position.

3. Assorting mechanism for fasteners having unequally spaced pairs of upstanding prongs, comprising a hopper having a passage, and a stop shaped to permit the passage

of fasteners in the passage only with the widely spaced prongs in advance.

4. Assorting mechanism for fasteners having widely and closely spaced pairs of prongs, comprising a hopper having a passage, and a stop projecting into the passage and being in diameter less than the distance between the widely spaced prongs and greater than the distance between the closely spaced

10 prongs.

5. Assorting mechanism for longitudinally unsymmetrical fastener parts comprising a hopper having means providing a passage wherein a fastener part must assume an angular position, and a stop so located as to contact with and prevent passage of a fastener part advancing with one end foremost and to clear and permit passage of a fastener part advancing with the other end foremost.

15 20 In testimony whereof I have signed my name to this specification.

EARLE M. CROSBY.
